United States Patent Office

Des. 183,368
Patented Aug. 12, 1958

183,368

TOY BANK

Carl F. Peterson and Karl Gust Bergman, Detroit, Mich.,
assignors to Duro Mold and Manufacturing, Inc., De-
troit, Mich.

Application October 17, 1957, Serial No. 48,147

Term of patent 14 years

(Cl. D34—11)

Fig. 1 is a front perspective view of a toy bank, showing our new design;

Fig. 2 is a rear perspective view;

Fig. 3 is a top plan view to a reduced scale; and

Fig. 4 is a bottom plan view thereof, to a reduced scale.

We claim:

The ornamental design for a toy bank, as shown.
